Primary Examiner — Ian Simmons*Assistant Examiner* — Carissa C Fitts(74) *Attorney, Agent, or Firm* — Leanne Taveggia Farrell; Westman, Champlin & Koehler, P.A.(57) **CLAIM**

The ornamental design for a task organizer, as shown and described.

DESCRIPTION

FIG. 1 is a perspective view of a task organizer;

FIG. 2 is a front view thereof;

FIG. 3 is a back view thereof;

FIG. 4 is a right side view thereof, the opposite side being a mirror image;

FIG. 5 is a top view thereof;

FIG. 6 is a bottom view of thereof; and,

FIG. 7 is an enlarged section view taken along line 7-7, with broken line subject matter removed.

The broken line showing is for environmental purposes only and forms no part of the claimed design.

1 Claim, 7 Drawing Sheets(56)
